UNITED STATES PATENT OFFICE.

BELLE M. STOVER, OF FAIR OAKS, CALIFORNIA.

HAT-PROTECTOR.

1,180,202.

Specification of Letters Patent.

Patented Apr. 18, 1916.

Application filed August 31, 1915. Serial No. 48,331.

To all whom it may concern:

Be it known that I, BELLE M. STOVER, a citizen of the United States, residing at Fair Oaks, in the county of Sacramento and 5 State of California, have invented new and useful Improvements in Hat-Protectors, of which the following is a specification.

This invention relates to improvements in cushions for hats.

10 The object of the invention is to provide a device which is adapted to be inserted between the sweat band or leather and the hat proper to preserve the hat from the perspiration which may penetrate the hat leather and at the same time provide a soft and agreeable substance between the head of the wearer and the hard body of the hat.

15 Another object of the invention is to provide a cushion which, while soft and yielding, is so as to make itself readily adjustable, comprises a non-absorbent device which may be constructed at a minimum cost and which requires no particular skill or instruments for positioning the same within the hat.

20 With the above and other objects in view, the invention resides in the novel construction of hat cushions hereinafter fully described and claimed.

25 In the drawing: Figure 1 is a view illustrating the improvement in applied position upon a hat, Fig. 2 is a perspective view of the improvement, and Fig. 3 is a transverse sectional view of the same.

30 In the drawing, the numeral 1 designates a hat and 2 the sweat band thereof.

35 The numeral 3 designates the cushion which is interposed between the hat band and the hat proper. The cushion 3 is constructed of an intermediate layer of oiled silk 4, layers of paper 5 arranged adjacent the opposite sides of the silk and outer

layers of near silk, designated by the numeral 6. These layers are secured together by a heat and pressure, such as heated irons or the like, and when completed, the article 45 provides a central thickened portion which curves upon one of its faces toward its opposite edges, the said curved face being of a crescent form. The edges of the article thus provided are bound through the medium of suitable tape 7, the latter being 50 stitched to the said article.

An article constructed as above described can be manufactured at an extremely small cost. The article is not susceptible to the 55 penetration of moisture, is elastic, is soft, and can be readily adjusted to accommodate itself to the various sizes of hats so that the same may be comfortably worn.

Having thus described the invention, what 60 I claim is:

A cushion member adapted to be inserted between the sweat band of a hat and the hat proper, constructed of a plurality of strips of non-absorbent material which are 65 arranged one against the other and subjected to heat and to pressure to form a cushion which is crescent-shape in plan, a continuous binding element surrounding the edges of the strips and having flanges which overlie the opposite faces of the cushions, and the said flanges being connected to the cushion by stitches which also pass transversely through the edges of the strips comprising the cushion. 70 75

In testimony whereof I affix my signature in presence of two witnesses.

BELLE M. STOVER.

Witnesses:

GEO. P. ROBINSON,
GEO. H. RICHARDS.
